UNITED STATES PATENT OFFICE

115,844

DESIGN FOR A COMBINATION CLEARANCE AND SIDE MARKER LAMP FOR MOTOR VE- HICLES

George F. Burgess, Cleveland, Ohio

Application May 25, 1939, Serial No. 85,200

Term of patent 7 years

To all whom it may concern:

Be it known that I, George F. Burgess, a citizen of the United States, residing at Cleveland, in the county of Cuyahoga and State of Ohio, have invented a new, original, and ornamental Design for a Combination Clearance and Side Marker Lamp for Motor Vehicles, of which the following is a specification, reference being had to the accompanying drawing, forming part thereof.

Figure 1 is a top plan view of a combination

clearance and side marker lamp for motor vehicles showing my new design;

Figure 2 is a front elevational view; and Figure 3 is an end elevational view thereof.

I claim—

The ornamental design for a combination clearance and side marker lamp for motor vehicles, as shown,

GEORGE F. BURGESS.
